WATER HEATER

Clarence H. Morrow, Shaker Heights, Ohio, assignor to The Hotstream Heater Company, Cleveland, Ohio, a corporation of Ohio

Application April 9, 1936, Serial No. 73,510

6 Claims. (Cl. 122—494)

This invention relates to improvements in water heaters and particularly to certain features of an enclosing cabinet structure combined with the heater combustion system.

Water heaters of the type including a water reservoir and a heating unit therebeneath when designed to reduce the overall height thereof, position the heating unit below the reservoir and relatively close to the surface upon which the heater is supported. These heaters are sometimes placed upon wooden floors and, to insure against fire hazard, building codes specify that the temperature of the floor below such burners shall not exceed a certain upper limit. My invention provides novel means for insuring against the overheating of the surface upon which the water heater rests.

When control equipment for heaters using gaseous or volatile fuel is housed within a cabinet there is an explosion hazard in case fuel should leak into unventilated pockets in the cabinet. My invention provides novel means for ventilating the portion of the cabinet housing the fuel supply and control equipment.

The novel structural features by which I carry out my invention will be more clearly understood from the accompanying drawing and specification and the essential features thereof will be set forth in the claims.

In the drawing, Fig. 1 is a sectional elevation of a water heating device embodying my invention; and Figs. 2, 3 and 4 are sectional views along similarly mounted lines of Fig. 1.

I have illustrated my invention as applied to that type of water heater which utilizes gas or similar fuel for the heating of the water, but it will be understood that a similar structure within the scope of the appended claims may be utilized with an electric or other heating unit.

In the form shown, a water reservoir 10 is supplied with the usual water inlet pipe 12 and outlet pipe 11. A cabinet 13 surrounds the entire unit and is provided with a removable front door 14 and the generally vertical transverse partition 15 forming a compartment adjacent the water reservoir and in which insulating material 16 may be packed if desired. A burner 17 is supported by a bracket 18 secured to a generally horizontal partition floor 13a of the cabinet 13 and the burner is supplied with a suitable fuel such as gas through a suitable connection 19. The usual control members, such as valves, thermostats, a pilot and the like, are indicated in the drawing but need not to be described here.

It is sufficient to say that the gas is supplied to

burner 17 in a well known manner and the supply of fuel is in accordance with the demand for hot water removed from the reservoir. The products of combustion from burner 17 pass upwardly through a flue 20 which is supplied with suitable damper means, as is usual.

The generally vertical transverse partition 15 and the generally vertical cylindrical reservoir partition 22, together with the generally horizontal partition 13a and the generally vertical side walls of the cabinet 13 and the lower head of the reservoir 10, form an upper chamber compartment substantially enclosing the burner 17. Generally vertical walls 13b, here shown as integral with the generally horizontal partition 13a, extend below the cabinet proper on all sides thereof and form a base which holds the cabinet, and the parts therein, slightly above the floor or other surface 23 upon which rests the present water heater, said walls 13b being provided with inwardly extending bottom flanges 13c, as shown. A lower chamber compartment 24 is therefore formed within the base and below the generally horizontal partition 13a thereof, as will be readily understood. One or more openings 25, three being here shown, are provided in the front end portion of the partition 13a, and the upper chamber compartment is provided with suitable openings 26 and 27, in the partitions 15 and 22, respectively, so that communication is provided between the lower chamber compartment and the upper chamber compartment. For the lower chamber compartment, suitable air inlet means remote from the openings 25 is provided, and in the embodiment here shown, air inlet openings 28 are provided in the rear base wall 13b, which wall is farthest removed from the openings 25, and other air inlet openings 29 are provided in the rear end portions of the side base walls 13b. It is to be understood, however, that any air inlet openings for the admission of secondary air to the lower chamber compartment, at a point or points removed from the opening or openings 25, are sufficient for the purpose, so long as a sufficient volume of secondary air is forced to flow across the lower surface of the partition 13a for the protection of the floor or other surface 23 upon which rests the present water heater.

With the above described construction, when the burner 17 is in operation, the products of combustion passing out the flue 20 cause convection currents in the direction of the arrows, Fig. 1, so that relatively cool secondary air for the burner 17 is caused to enter the lower chamber compartment through the inlet openings 28

or 28 or both, said secondary air passing to the left as viewed in Fig. 1 beneath the partition 13a, then through the openings 28, 26 and 27 to the upper chamber compartment, in which the 5 burner 17 is located, and thence out through the flue. Such a current of cool air passing below the partition 13a will cool the partition, which would normally be a metal plate, and thus protect the floor or other surface 23 from excessive 10 heat due to the close proximity of burner 17.

As an additional protection to minimize the heat reaching the floor or other surface 23 from the burner 17, I provide heat insulation 31 between the burner 17 and the floor or other surface 23. This insulating material, if desired, may be incased in a metal housing 32, as here shown, and securely bolted to the partition 13a by the members 33.

I find that by utilizing the construction above 20 described, I can place the water reservoir of the heater very close to the floor 23, which places the burner 17 still closer to the floor, but with the protection here shown and described I am able to hold the temperature of the floor at a point 25 low enough to prevent charring or burning of a combustible floor 23 and well below the temperatures specified in those building codes with which I am familiar.

It will be noted that in the front or left portion of the cabinet 13 as viewed in Fig. 1, a 30 chamber 21 is formed between the door 14 and the transverse partition 15, which chamber 21 houses the fuel supply and control equipment. If the space in this chamber is dead space, any 35 leakage of fuel therein may cause a dangerous condition. To avoid such a contingency, one or more openings 36 for the ingress of air into chamber 21 may be provided, and by locating the openings 36 at a point removed from the source of 40 suction, namely, from the opening 26 in the partition 15 which leads to the upper chamber compartment and to the flue 20, I insure good ventilation for chamber 21. By making the air inlet openings 28 and 29 insufficient to supply a proper 45 amount of secondary air to the burner 17 and less than the capacity of flue 20, I insure that some secondary air will be drawn through openings 36. At the same time, the openings 36 are small enough to insure sufficient draft through 50 the air inlet openings 28 and 29 to create the cooling effect desired in the lower chamber compartment for the proper protection of the floor or other surface 23, all as will be readily understood.

55 What I claim is:

1. In a water heater having a water reservoir and a water heating unit therebeneath and located a relatively short distance above a floor or other surface, a casing forming a substantially 60 closed chamber between said reservoir and said heating unit, a partition beneath said heating unit and spaced from said floor or other surface and dividing said chamber into an upper burner compartment between said reservoir and said partition and a lower air compartment between said partition and said floor or other surface, a heat insulating member under said heating unit and adjacent said partition, a flue communicating 65 with said upper compartment for the flow therefrom of products of combustion, an air passageway establishing communication between said upper and lower compartments for the flow of air from the lower compartment to the upper compartment, and air inlet means for said lower com- 70

partment and remotely located relative to said air passageway, whereby said floor or other surface is protected from the heating effects of said heating unit by said insulating member and by the air which enters the lower compartment 5 through the air inlet means thereof and which passes beneath said partition to said air passageway and thence into said upper compartment.

2. In a water heater having a water reservoir 10 and a fuel burner unit therebeneath and located a relatively short distance above a floor or other surface, a casing forming a substantially closed chamber between said reservoir and said floor or other surface and enclosing said burner unit, a partition beneath said burner unit and spaced above said floor or other surface and dividing said chamber into an upper burner compartment between said reservoir and said partition and a lower air compartment between said partition and said floor or other surface, said partition under said burner unit being uninterrupted, a flue 15 communicating with said upper compartment for the flow therefrom of products of combustion, an air passageway through said partition 20 establishing communication between said upper and lower compartments for the flow of air from said lower compartment to said upper compartment, and air inlet means in said casing and below said partition for the lower compartment, said air inlet means being remotely located relative to said air passageway, whereby air drawn through said inlet means into said lower compartment flows beneath said partition, with a cooling effect thereon, to said air passageway and thence into said upper compartment. 25

3. In a water heater having a water reservoir and a fuel burner unit therebeneath, a cabinet enclosing said reservoir and said burner unit, partition means providing an upper compartment in which said burner unit is located and a lower compartment, air inlet means for said lower compartment and a products of combustion outlet means for said upper compartment, and an air passageway establishing communication between said lower and upper compartments for the flow of air from said lower compartment to said upper compartment, the air inlet means for said lower compartment being remotely located relative to said air passageway, the two compartments being otherwise sufficiently closed so that a large proportion of the secondary air supplied to said burner unit flows through said lower compartment and across the lower surface of said partition means, with the consequent production of a cooling effect upon said partition means. 30

4. In a water heater having a water reservoir and a compartment therebeneath in which is located a fuel burner, said water heater also having a flue communicating with said compartment for the flow therefrom of products of combustion, control apparatus for the supply of fuel to said burner, cabinet means having a chamber for said control apparatus, there being an air passageway between said chamber and said burner compartment and there being an air inlet means in said cabinet means for the flow of air into said chamber, the air inlet means of said cabinet means being remotely located relative to said air passageway. 40

5. A water heater as in claim 4, characterized in that partition means is provided which forms an air compartment beneath said burner, air inlet means for such air compartment, means estab- 45

lishing communication between said air compartment and said burner compartment, said air inlet means for said air compartment being insufficient to supply said burner with a proper amount 5 of secondary air, whereby secondary air for said burner is also supplied through the air inlet means of said cabinet means.

6. In a water heater having a water reservoir and a water heating unit therebeneath and located a relatively short distance above a floor or other surface, a casing forming a substantially closed chamber between said reservoir and said floor or other surface and enclosing said heating unit, a heat insulating partition beneath said unit 10 and spaced from the floor or other surface and dividing said chamber into an upper burner compartment between said reservoir and said parti-

tion and a lower air compartment between said partition and said floor or other surface, a flue communicating with said upper compartment for the flow therefrom of products of combustion, an air passageway at one side of said casing establishing communication between said upper and lower compartments for the flow of air from the lower compartment to the upper compartment, and an air inlet opening for said lower compartment remotely located relative to said air passageway, whereby the floor or other surface is protected from the heating effects of said heating unit by said insulating partition and by the air flowing beneath said partition from the lower compartment to the air passageway and thence 15 into the upper compartment.

CLARENCE H. MORROW.
